UNITED STATES PATENT OFFICE.

LUDWIG BAKER, OF EAST SAGINAW, MICHIGAN, ASSIGNOR TO THE WICKES BROTHERS, OF SAME PLACE.

STATIONARY BOILER.

SPECIFICATION forming part of Letters Patent No. 579,784, dated March 30, 1897.

Application filed April 20, 1896. Serial No. 588,223. (No model.)

To all whom it may concern:

Be it known that I, LUDWIG BAKER, of East Saginaw, Michigan, have invented certain new and useful Improvements in Steam-Boilers, of which the following is a specification.

This invention relates to improvements in stationary boilers; and the object of the invention is to provide a boiler in which a rapid circulation may be effected and maintained, in which an effective separation of the steam and water may be made, and which is of such construction as to afford ready means for cleaning.

To this end my invention consists in a boiler having in combination and substantially as hereinafter described a steam and water drum, front and back headers communicating with the drum, and tubes connecting said headers, the front header being of less relative capacity than the back header, whereby a relatively smaller body of water is maintained in the front header than in the back header and a better circulation and separation of steam from the water and a sufficient water-supply for all tubes are maintained.

Figure 1 is an elevation, sectional, through the drum, the headers, and the necks connecting them with the drum and showing the tubes and stays in elevation. Fig. 2 is a front elevation of the boiler, partly in vertical section, through the front plate.

In the drawings, 3 represents the steam and water drum, of cylindrical outline and horizontal arrangement.

4 represents the water-space of the front header, and 5 the water-space of the back header. These headers are made of wrought-steel plates, the front header having the perforated front plate 6, with flanged neck 7, and an inner plate 8, perforated to receive the tubes 9. Said plates 6 and 8 have rivet-flanges turned outwardly where they join the walls of the drum and their proximate margins turned inwardly and abutted, the joint being covered by the band or shell 10, riveted to the inturned margins. The water-tubes are arranged in parallel horizontal rows and staggered vertical rows, and the front plate 6 is provided with a series of hand-holes 11, one for each tube, each hand-hole being pro-

vided with a cap or cover 12. Suitable stays 13 are also employed connecting the plates 6 and 8. The rear header is composed of a flanged plate 14, a dished plate 15, and the overlap or shell 16, the dished plate 15 being provided with manhole 17 and the shell 16 being provided with flange for blow-off 18. The water-space of the rear header is connected with the interior of the drum by means of the neck 19.

It will be observed that the headers are of unequal capacity, the front header having a water-space of much less transverse diameter or depth than that of the rear header. As a result a large volume of water is maintained at all times in the rear header and an adequate supply of water is maintained in the tubes 9. The smaller volume of water in the front header offers but little resistance to the passage of steam from the tubes to the drum, and a more rapid circulation and a better separation are thereby effected. This will be understood when it is considered that the body of water in the front header acts as a resistance to the passage of the steam from the tubes to the drum and that the thinner this body of water is the less pressure is exerted against steam issuing from the ends of the tubes, while the steam will more readily separate from the liquid body. The front header being relatively thin and the open ends of the tubes close to the hand-holes in the front plate, they may be readily cleaned.

It is obvious that my invention might be embodied in modified constructions, but the essential feature is the provision of headers of unequal capacity, the front header serving to contain the relatively thin body of water, while the rear header contains the larger body, adequate to supply the tubes under all conditions of firing.

I claim—

1. A steam-boiler comprising in combination a horizontally-arranged cylindrical drum, headers having contracted necks connecting with the drum by a single inlet, the transverse diameters of said headers being short as compared with their width and the front header being of less transverse diameter or depth than the rear header and containing in

operation a thin body of water and tubes connecting said headers substantially as and for the purpose described.

2. A steam-boiler comprising in combination a horizontally-arranged drum, a front header connecting therewith, a back header also connecting therewith, said headers being of circular outline and having contracted necks forming their connection with the drum, inclined water-tubes connecting the

water-space of said headers, and said front header being of less transverse diameter or depth than the rear header, and the front plate of said header being provided with hand-holes opposite the open ends of the water-tubes substantially as described. 15

LUDWIG BAKER.
